DRILL PULLER

Louis Sovincez, Los Angeles, Calif.

Application July 2, 1937, Serial No. 151,761

4 Claims. (Cl. 254—30)

This invention relates to improvements in drill pullers and more particularly a device to be used for removing drills from rock and earth which have become frozen against dislodgment.

5 The primary object of this invention is to provide a drill puller of the above mentioned character including an upright post to which is pivoted a fulcrum bar carrying a pair of drill gripping dogs capable of effecting a vertical straight line pull on the drill.

10 A further object of this invention is to provide a drill puller of the above mentioned character having means for exerting force in an upward direction to the fulcrum bar whereby said means may exert more power thereto due to the fact that it is supported on the ground or earth from whence the drill is being removed.

15 A still further object of this invention is to provide a handle to be used in conjunction with the above mentioned means in order that the fulcrum bar may be oscillated after the drill has been loosened from its frozen position.

20 Other objects and advantages of the invention will become apparent during the course of the following description taken with the drawing, wherein

25 Figure 1 is a side elevational view of the device embodying this invention, showing a portion broken away to illustrate the location of the drill gripping dogs;

30 Figure 2 is a plan view of the same and shows the manner in which the drill gripping dogs are carried by a pivotal plate carried by the fulcrum bar, and

35 Figure 3 is a vertical cross-sectional view taken on lines 3—3 of Figure 1 looking in the direction of the arrows and illustrating the manner in which the fulcrum bar is pivotally connected to the upper forked end of the supporting post.

40 In the drawing, wherein for the purpose of illustrating the invention and wherein like reference characters will be employed to designate like parts throughout the same, the reference character 5 will generally be employed to designate a fulcrum bar supporting post having the lower end flared outwardly as at 6 and terminating in a flanged portion 7 capable of resting on the plank 8 supported on the ground or earth 9 in proximity to a drill D, the removal of which is desired.

45 The upper end of the supporting post 5 is forked as at 10 for receiving a fulcrum bar 11 held in place by a fulcrum pin 12. One end of the fulcrum pin 12 is threaded for receiving a nut 13 and a lock washer 14 is interposed between the

5 nut 13 and forked member 10. A boss 15 is formed on the fulcrum lever 11 to properly space the same between the forked end 10 of the supporting post 5 and the boss is arranged in such a manner as to allow the pivot pin 12 to extend through the central opening 16 formed therein.

Journalized on the fulcrum lever 11 is a dog-carrying plate 17 having an opening 18 formed intermediate its ends for receiving a pivot pin 19 extending through a central opening 20 formed in 10 a boss 21 on the fulcrum lever 11. Bracing ribs 22 are disposed on the fulcrum lever 11 and extend longitudinally thereof on opposite sides of the boss 20 so that their inner ends terminate in the boss. One end of the pivot pin 19 is provided 15 with a head 23 which is received in a recess 24 communicating with the opening 18. The opposite end of the pin 19 is threaded as at 25 for receiving a locking nut 26.

20 Secured to the ends of the dog-carrying plate 20 17 are pins 27 and 28 adapted to carry a pair of dogs 29 having drill engaging teeth 30 presented to the drill D at an angle to cause the drill to be locked in place and the teeth grip of the drill to prevent slippage. The dog-carrying pins 27 and 25 28 are provided with bosses 31 to prevent displacement of the dogs 29 against lateral movement.

25 It will be noted that the pin 28 is extended a short distance for receiving a strain plate 32 30 having an opening 33 at one end and an opening 34 at the opposite end. The pin 28 is received in the opening 33 while the opposite end of the plate has its opening 34 passed over the screw-threaded portion 35 forming an extension of 35 the pin 27. A nut 36 may be threaded on the screw-threaded extension 35 to allow removal of the strain plate 32 when the device is being positioned for operation upon a frozen drill D.

30 The free end of the fulcrum lever 11 is provided 40 with an off-set portion 37 having an extension 38 for accommodating means for exerting an upward force such as a screw jack or the like. The extension 38 is centrally drilled as at 39 for receiving a handle 40 whereby a series of vertical 45 movements may be accomplished after the frozen drill D has been loosened.

35 In the present instance a screw jack 41 is employed for exerting a force in the direction of the arrows upon the free end of the fulcrum lever 50 and said screw jack comprises a base 42 fastened or otherwise secured to an elongated plate 43. In order to prevent the elongated plate 43 from being pressed into the ground when the device is in operation, a plank or board 44 having a 55

large surface area is mounted beneath the elongated plate 43. A rotary screw-threaded bar 45 is rotatably mounted in the screw jack 41 and is adapted to be rotated by means of bevel gears 46 manually operable by means of a crank 47. Formed on the upper end of the screw-threaded bar 45 is a swivel coupling comprising parts 48 and 49 between which is mounted ball bearings 50 to allow free rotation of the screw-threaded bar 45 relative to the part 48. A lug 51 is formed on the section 48 of the swivel connection and extends between a pair of depending lugs 52 formed on the extension 38. A pin 53 or other fastening means may be provided for coupling the lug 51 to the depending lugs 52.

15 The jack structure is normally separate from the extension 38 of the fulcrum bar 11, but is readily attached thereto by means of the pin 53 inserted in the lugs 51 and 52. When the jack is separated from the fulcrum bar, the extension end 38 moves downwardly, the fulcrum bar being prevented from complete collapse by reception in the notch 10a in one side of the fork 10 for support in an inclined position as will be evident from an inspection of Figure 1. The fulcrum bar is then prevented from moving laterally with respect to the post 5 so that injury to the bearing boss 15 will be eliminated.

20 It will be understood that the drill rod D will not be bent or twisted during its removal from the bore hole in view of the fact that the dogs 29 will maintain a parallel relationship irrespective of the movement of the fulcrum lever 11 and that the strain plate 32 will prevent undue 25 stresses upon the dog-carrying pins 27 and 28.

25 It will also be understood that the device shown in the drawing is to be taken as the preferred embodiment of the invention but obviously changes in the shape, size and arrangement of 30 parts may be resorted to without departing from the spirit of the invention or the scope of the 35 subjoined claims.

I claim:

30 1. A drill puller of the character described, comprising a support, a lever having one end ful-

crummed to the upper end of the support, means carried by the free end of the lever for exerting a vertical force thereto, a dog-carrying plate pivoted intermediate the ends of the lever, and a pair of dogs pivotally attached to the ends of the 5 dog-carrying plate for engaging a drill.

2. A drill puller of the character described, comprising a vertical support, a fulcrum lever having one end pivotally attached to the vertical support, means for exerting a vertical force 10 to the free end of the fulcrum lever, a dog-carrying plate pivotally attached intermediate the end of the fulcrum lever, a pair of drill-gripping dogs pivotally mounted on the dog-carrying plate and means for preventing displacement of the dogs 15 away from the drill.

3. A drill puller of the character described, comprising a vertical supporting post, a fulcrum lever, having one end pivotally attached to the vertical supporting post, an offset portion formed adjacent the free end of the fulcrum lever, an extension in direct alinement with the vertical supporting post formed on the offset portion, a pivoted dog-carrying plate mounted intermediate the ends of the fulcrum lever, a pair of 20 work gripping dogs pivotally attached to the dog-carrying plate and means for exerting a vertical 25 force to the fulcrum lever extension.

4. A drill puller of the character described, comprising a vertical supporting post having a 30 forked upper end, a fulcrum lever pivotally secured between the fork, an offset portion formed on the opposite end of the fulcrum lever, an extension in direct alinement with the forked end of the vertical supporting post formed on the 35 opposite portion, an elongated plate pivoted to the fulcrum lever intermediate its ends, a pin carried by each end of the elongated plate, a dog mounted on each of the pins having gripping teeth for engaging the work, a plate connecting the free ends of the pins to prevent opposed 40 stresses applied to the pins and means carried by the extension for exerting a vertical force to the extension of the fulcrum lever.
